UNITED STATES PATENT OFFICE.

RICHARD R. LAMB, OF ARROWSMITH, ILLINOIS.

CEMENT-FINISHING TOOL.

1,239,608.

Specification of Letters Patent. Patented Sept. 11, 1917.

Application filed July 21, 1916. Serial No. 110,574.

To all whom it may concern:

Be it known that I, RICHARD R. LAMB, a citizen of the United States, residing at Arrowsmith, in the county of McLean and 5 State of Illinois, have invented certain new and useful Improvements in Cement-Finishing Tools, of which the following is a specification.

This invention relates to certain new and 10 useful improvements in cement finishing tools.

The primary object of this invention resides in the provision of a cement finishing tool which will be of simple construction, 15 may be readily adjusted with the handle extended at any desired angle and which will be highly efficient in use.

Another object of the invention resides in the provision of a means whereby a single 20 connection may be formed between the same and the handle and the latter readily adjusted to any desired angle.

A further object of the invention resides in the provision of a joint or connection between the tool and the handle whereby a 25 single long handle may be employed and removably connected with any one of the tools.

With these general objects in view and 30 others that will appear as the nature of the invention is better understood, the same consists in the novel combination and arrangement of parts hereinafter more fully described, illustrated in the accompanying 35 drawings and pointed out in the appended claim.

In the drawings forming a part of this application and in which like-designating characters refer to corresponding parts 40 throughout the several views, in which:—

Figure 1 is an elevation partly in section, showing the handle applied to one of the cement finishing tools.

Fig. 2 is a plan view of another cement 45 finishing tool constructed to receive my improved form of handle.

Fig. 3 is a plan view of a portion of another form of cement finishing tool adapted to receive my new form of handle.

50 Fig. 4 is a longitudinal section through the tool part shown in Fig. 3.

Fig. 5 is an enlarged elevation of a further form of cement finishing tool.

Fig. 6 is a side elevation of the form of

tool shown in Fig. 5 with the handle applied thereto. 55

Fig. 7 is a plan view of a corner finishing tool.

Fig. 8 is a sectional view through the same substantially on the plane of line 8—8 of 60 Fig. 7.

Fig. 9 is a plan view of another form of corner finishing tool adapted to receive my improved form of handle, and

Fig. 10 is a sectional view through the 65 tool shown in Fig. 9, substantially on the plane of line 10—10 of Fig. 9.

Referring more in detail to the drawings, 1 designates the core of the handle which may be formed of any suitable material and 70 may either be solid as shown or hollow as preferred. Clamped upon opposite sides of the core 1, are the longitudinally extending connecting members 2 which are preferably of semi-circular form in cross section, said 75 connecting members being clamped upon the core 1 by suitable bolts 3, one or more of which may be extended through the core 1, said screws 3 having suitable heads 4 formed upon one end, while thumb nuts 5 or the 80 like, are threaded upon their opposite ends. The lower ends of the connecting members 2 are extended past the lower end of the core 1 and provided with concaved recesses 6 in their inner faces to receive the spherical 85 members 7 formed on a stem 8 which is secured in any suitable manner in a socket 9 formed upon the upper face of the cement finishing tool 10. It will be understood that the extended end of each connecting member 90 2, is provided with a central oil or lubricant-receiving opening 11, whereby suitable lubricant may be supplied to the spherical member 3 to reduce friction to the minimum.

While I have not shown the handle applied to all of the different cement finishing tools shown in the drawings, it will be evident that the handle may be connected to each in the same manner and by loosening the nut 5 upon the lowermost bolt 3, the 95 handle may be readily turned to any angle desired with respect to the upper face of the tool 10 and then securely locked in adjusted position by again tightening the nut 5. 100

While the form of the invention herein shown and described is what is believed to be the preferred embodiment thereof, it is nevertheless to be understood that minor 105

changes may be made therein without departing from the spirit and scope of the invention as claimed.

What I claim as new is:—

5. In a cement-finishing tool, the combination with a tool having a flat upper surface and a socket centrally positioned thereon, of a stem having its lower end received in said socket and equipped at its upper end with a spherical head, a cylindrical handle, a pair of semi-cylindrical clamping members embracing opposite sides of said handle adjacent its lower end, said clamping members having their laterally curved edges extending in spaced parallelism and having their lower ends extending beyond the lower end

of said handle, the said lower ends of the clamping members being thickened and provided on their inner faces with opposed concaved recesses adapted to be oppositely engaged with said spherical head, a fastening bolt passing through said handle and the upper ends of said clamping members, and an adjusting bolt passing through the lower ends of said clamping members and engaged with the lower end of said handle. 20 25

In testimony whereof I affix my signature in presence of two witnesses.

RICHARD R. LAMB.
